(57) **CLAIM**

The ornamental design for an ultrasonic transducer, as shown and described.

DESCRIPTION

FIG. 1 is a front, top perspective view for an ultrasonic transducer showing my new design;

FIG. 2 is a front, bottom perspective view thereof;

FIG. 3 is a front elevational view thereof;

FIG. 4 is a top plan view thereof;

FIG. 5 is a bottom plan view thereof;

FIG. 6 is a cross-sectional view thereof taken along at A-A of FIG. 1; and,

FIG. 7 is a reference front, top perspective view showing an example of usage thereof.

The broken lines in the figures are for the purpose of illustrating environmental structure and form no part of the claimed design.
